(57) **CLAIM**

The ornamental design for a disc-shaped pet toy, as shown and described.

DESCRIPTION

FIG. 1 is a perspective view depicting the top, front, and right side of a disc-shaped pet toy;

FIG. 2 is a top plan view of the disc-shaped pet toy of FIG. 1;

FIG. 3 is a bottom plan view of the disc-shaped pet toy of FIG. 1;

FIG. 4 is a left side view of the disc-shaped pet toy of FIG. 1;

FIG. 5 is a right side view of the disc-shaped pet toy of FIG. 1;

FIG. 6 is a front view of the disc-shaped pet toy of FIG. 1; and,

FIG. 7 is a rear view of the disc-shaped pet toy of FIG. 1. The broken lines are for illustration only and form no part of the claimed design.
